US00D988453S

(12) **United States Design Patent** (10) **Patent No.:** **US D988,453 S**
(45) **Date of Patent:** **** Jun. 6, 2023**

(54) **TOP SUPPORT STRUCTURE OF TENT FRAME**

(71) Applicant: **Zhejiang Kedi Leisure Products Co., Ltd.**, Jinhua (CN)

(72) Inventor: **Xinghua Han**, Jinhua (CN)

(73) Assignee: **ZHEJIANG KEDI LEISURE PRODUCTS CO., LTD**, Jinhua (CN)

(**) Term: **15 Years**

(21) Appl. No.: **29/868,626**

(22) Filed: **Dec. 9, 2022**

(51) LOC (14) Cl. **21-04**

(52) U.S. Cl.

USPC **D21/839**

(58) **Field of Classification Search**

USPC D21/834, 837-840

CPC E04H 15/00; E04H 15/06

See application file for complete search history.

(57) **CLAIM**

The ornamental design for a top support structure of tent frame, as shown and described.

DESCRIPTION

FIG. 1 is a perspective view of a top support structure of tent frame showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

1 Claim, 8 Drawing Sheets
